UNITED STATES PATENT OFFICE

JOHN J. GRANTONIC, OF MINGO JUNCTION, OHIO

MECHANICAL POOL BALL RACKING DEVICE

Application filed December 31, 1930. Serial No. 505,954.

This invention relates to a mechanical pool ball racking device and has for an important object to provide, in a manner as hereinafter set forth, a device of this character embodying a novel construction and arrangement of parts for conveying a pool ball which has been pocketed from a pool table and selectively depositing said ball in any desired compartment of a rack which is mounted on a suitable support adjacent the pool table and above the horizontal plane of said pool table.

Another important object of the invention is to provide a mechanical pool ball rack device of the character described embodying novel means for removing the balls from the wall rack when a new game is to be started and manually racking the balls in position on the table.

Other objects of the invention are to provide a mechanical pool ball racking device of the character set forth which will be simple in construction, strong, durable, efficient and reliable in use and which may be manufactured and installed at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in front elevation showing the major portion of the apparatus constituting the present invention.

Figure 2 is a view similar to Figure 1 with portions of the apparatus broken away in vertical section.

Figure 3 is a view in perspective showing a pool table with which the device is operatively connected, said pool table having mounted thereon switches for controlling the apparatus.

Figure 4 is a fragmentary detailed view in horizontal section taken substantially on the line 4-4 of Figure 1 looking downwardly.

Figure 5 is a fragmentary view in vertical section taken substantially on the line 5-5 of Figure 1.

Figure 6 is a fragmentary view in vertical

section through the wall rack showing the means of discharging the balls therefrom when said balls are to be reracked on the pool table.

Figure 7 is a fragmentary detail view in vertical longitudinal section showing the closure provided in the pool table tray for preventing the discharge of the balls from said trays to the apparatus constituting this invention when said apparatus is not to be used.

Figure 8 is a detail view in top plan showing a table ball rack which is used with the apparatus in closed position.

Figure 9 is a view in top plan of the table ball rack in open position.

Figure 10 is a view in side elevation of the table ball rack.

Referring to the drawings in detail, it will be seen that the reference numeral 1 designates a pool table having the conventional pockets 2 therein which communicate through the usual channels or conduits with an inclined tray 3 to the bottom of the free end portion of which the upturned portion 4 of an inclined pipe 5 extends for communication with the tray 3 in a manner to receive balls therefrom by gravity. A substantially V-shaped guide 6 is disposed in the tray 3 for directing the balls into the pipe 5. A cover 7 is provided for removable disposition on the tray 3 to prevent foreign matter, such as a chalk, from falling thereinto and getting into the conduit 5 and obstructing said conduit. It may be well to here state that a suitable closure 8 is provided which is inserted in the upper end portion of the upturned portion 4 of the conduit 5 in the tray 3 when the apparatus constituting this invention is not to be used. The inclined portion of the conduit 5 extends beneath the floor 9 of the building or other structure. The pool table 1 further includes the usual rails 10.

A supporting panel or structure 11 is mounted vertically on a wall or other support by any suitable means and mounted vertically thereon in spaced relation thereto is a wall rack which is designated generally by the reference numeral 12. Suitable bars, as at 13, (see Figure 4) may be provided

ed for supporting the wall rack 12 in position.

The rack 12 comprises a plurality of vertically spaced, inclined partitions 14 which provide the compartments 15 for the reception of the balls 16, the upper sides of the partitions 14 having channels or grooves therein through which the balls travel. The compartments 15 are open at their upper ends and are closed at their lower ends by a reciprocating closure bar 17 which, as best seen in Figure 6 of the drawings, is mounted on the horizontal rods 18 which extend slidably into the chambers 19 of the upper and lower members 20 of the rack 12 and have oppositely engaged therewith the coil springs 21 which yieldingly urge the closure bar 17 into engagement with the adjacent ends of the partitions 14 for closing the lower ends 20 of the compartments 15 and thus retain the balls 16 in said compartments. The coil springs 21 are, of course, housed in the chambers 19 and encircle the rods 18 and have one end engaged with one end of the chambers 19 and their other ends engaged with an abutment or head provided therefor on the rods 18. An operating handle 22 is fixed on the closure bar 17 for actuating said closure bar.

An elevator designated generally by the reference numeral 23 is disposed vertically adjacent the open ends of the compartments 15 of the wall rack 12 and said elevator is spaced from said wall rack. The elevator 23 comprises a vertically disposed elongated casing 24 having its upper portion extending adjacent to or in abutting engagement with the supporting panel or structure 11 and secured thereto by any suitable means, as by a bracket 25. The casing 24 extends downwardly through the floor 9 and is supported on a flange 26. The inner periphery of the casing 24 has formed therein a vertically extending substantially semi-circular groove or channel 27 which has one end portion extending through the floor 9 and terminating in spaced relation to the lower end of the casing 24. The inclined conduit 5 is provided with an upturned end portion 28 which communicates with the lower end of the groove or channel 27 and with the lower portion of the casing 24. At its upper end the groove or channel 27 merges into a laterally extending, inclined discharge neck or spout 29 which extends toward the open end 55 of the uppermost compartment 15 of the wall rack 12 and terminates in spaced relation thereto. As best seen in Figure 5 of the drawings, a ball deflector 30 is formed integrally on the upper end of the groove or channel 27 and extends into the casing 24.

A spiral or worm conveyor 31 is operatively mounted in the casing 24 of the elevator 23 and is actuated by a drive shaft 32 which is journaled in a bearing block 33 at the upper end of the casing 24 (see Figure 5). An

electric motor 34 is supported in vertical position on the supporting panel or structure 11 and has oppositely connected to the lower end of its armature shaft a worm shaft 35 which is journaled in a bearing block 36 mounted on the bearing block 33. The bearing blocks 33 and 36 are provided with a gear chamber in which are housed the gears 37 for operatively connecting the shaft 32 to the worm shaft 35 for actuation by the electric motor 34. A hand wheel 38 is fixed on the upper end of the armature shaft of the motor 34 to provide means for manually actuating the spiral or worm conveyor 31.

A guide cylinder 39 depends from the supporting panel or structure 11 adjacent the ball elevator 23 for slidably receiving the lower portion of a vertically movable rack bar 40 of polygonal cross section having an extension 41 of circular cross section depending from its lower end and projecting slidably through the lower end of the guide 39. A bridge member 42 is rigidly mounted on the upper end of the rack bar 40 for travel between the open upper ends of the compartments 15 of the wall rack 12 and the upper portion of the elevator 23. The upper side of the bridge member 42 is provided with a channel or groove 43 which inclines toward the wall rack 12. Rigidly mounted vertically on the side of the casing 24 of the elevator 23 which is adjacent the wall rack 12 is a bar 44 having therein the substantially V-shaped notches 45 for receiving the substantially arrow-shaped spring pressed keeper 46 which is slidably mounted in the bridge member 43. It may be well to here state that the bridge member 42 is disposed at all times beneath the discharge end of the neck 29 in a manner to receive the pool balls therefrom.

A vertically disposed housing 47 is provided for slidably receiving a flat, elongated plate 48 having its lower end rigidly mounted on the bridge member 43 and bifurcated to provide an opening 49 for the passage of the pool balls to the compartments 15 of the wall rack 12 with which the bridge member 43 has been positioned.

An electric motor 50 is mounted on the supporting panel or structure 11 and is operatively connected to the rack bar 40 in the manner to actuate said rack bar by a pinion gear 51. A hand wheel 52 is secured to the armature shaft of the electric motor 50 in order that the rack bar 40 may be manually actuated when it is so desired. It may be well to here state that the motor 34 which drives the spiral or worm conveyor 31 rotates in one direction only but the electric motor 50 is of the reversible type. Switch buttons 53 and 54 are mounted in the rail 10 of the pool table 1 or at any other desired points. The switch buttons 53 are connected with the reversible electric motor 50 for causing rotation of said motor in one direction and the switch buttons 130

54 are electrically connected with the motor 50 in a manner to cause rotation of said motor 50 in the opposite direction. The buttons 53 and 54 are identified by suitable indicia 55
 5 in order that the motor 50 may be actuated in the desired direction for raising or lowering the rack bar 40 and the bridge member 42. The electric motor 34 is constantly in operation during the playing of a pool game
 10 and is controlled by a switch 56 on the panel or structure 11 as best illustrated in Figure 1 of the drawings.

A shelf 57 is mounted horizontally on the supporting panel or structure 11 beneath the discharge end of the wall rack 12 for supporting a table rack which is designated generally by the reference numeral 58 and illustrated to advantage in Figures 8 to 10 inclusive of the drawings. The table rack 58 comprises a substantially triangular frame 59 to the front and rear of which are fixed the horizontally disposed bars 60 which slidably support the complementary shiftable bottom sections 61 through the medium of the upturned eyes 62 which are provided on the front and rear ends of the bottom sections for the reception of the bars 60. Handles 63 are provided on the outer edges of the bottom sections 61 for shifting said bottom sections 25
 30 between the positions illustrated in Figures 8 and 9 of the drawings.

In use, the closure 8 is removed from the riser 4 of the inclined conduit 5 and when a player pockets a ball he closes one of the switches 53 or 54 to energize the motor 50 and actuate the rack bar 40 to raise or lower the bridge member 42 until said bridge member is disposed in proper position adjacent the compartment 15 of the wall rack 12 in which 35
 40 the player wishes to keep the balls which he has pocketed. When the bridge member 42 is in proper position adjacent the desired compartment 15 the switch 53 or 54 is released to de-energize the electric motor 50 and the bridge member 42 is retained in the correct position by the spring pressed keeper 46 which seats in the correct notch 45 of the bar 44. The shape of the head of the keeper 46 and the notches 45 are such that the proper 45
 50 positioning of the bridge member 42 relative to the compartments 15 will be assured and expedited. When the switch 56 is closed, the electric motor 34 is also, of course, energized to actuate the spiral or worm conveyor 31 of the elevator 23. The ball or balls which may have been pocketed gravitate in the usual manner to the tray 3 and are directed by the guide 6 into the riser 4 and said ball or balls pass downwardly through the 55
 60 inclined conduit 5 into the groove or channel 27 on the casing 24. The balls will protrude into the casing 24 from the groove or channel 27 and will be engaged by the spiral or worm conveyor 31 and carried upwardly and discharged through the neck 29. From the dis-

charge neck 29 the balls drop onto the bridge member 42 and roll therefrom by gravity into the compartment 15 of the wall rack 12 from which the bridge member 42 has been positioned. In passing from the bridge member 70
 75 42, the balls pass through the openings 49 provided by the bifurcated lower end of the elongated plate 48. When the bridge member 42 is positioned to direct the balls in any of the compartments 15 of the wall rack 12 which are disposed below the uppermost compartment 15, the elongated plate 48 is disposed over the open ends of the compartments or compartment 15 which are disposed above the compartment in which the ball is 80
 85 to be directed for closing the same and preventing the entrance of the balls thereinto.

A cover plate 64 is disposed in front of the rack bar 40 and the bridge member 42 and extends between the wall rack 12 and the upper portion of the casing 24 of the elevator 23. The cover plate 64 is provided with a vertically extending slot 65 adjacent which are arranged the numerals 66 which are arranged in order and which designate the compartments of the wall rack 12. An indicator 67 is fixed on one side of the bridge member 52 and is operable through the slot 65 and cooperates with the numerals 66 for indicating when the bridge member 42 is in proper position relative to the desired compartments 15. A light 68 is provided on the upper portion of the cover plate 64 for illuminating the numerals 66 and the indicator 67. 90
 95
 100

When a new game is to be started, the table rack 58 is disposed on the shelf 57 in the manner illustrated to advantage in Figure 1 of the drawings with the bottom sections 61 in closed position, as seen in Figure 8 of the drawings. The closure bar 17 is then moved outwardly against the tension of the coil springs 21 to the position clearly seen in Figure 6 of the drawings to open the lower ends of the compartments 15 to permit the balls to be discharged into the table rack 58. The table rack 58 with the balls therein is then carried to the pool table 1 and disposed thereon in the desired position. The bottom sections 61 are then moved outwardly to the position illustrated in the Figure 9 of the drawings to deposit the balls on the table and permit the removal of the frame 59 therefrom. As before stated, the hand wheels 38 and 52 provide means for manually actuating the ball racking mechanism. 110
 115
 120
 125

It is believed that the many advantages of a device in accordance with this invention will be readily understood and, although the preferred embodiment of this invention is as illustrated and described, it is to be understood that changes in the details of construction may be had which will fall within the scope of the invention as claimed.

What is claimed is:

1. A ball racking device for pool tables comprising a rack having a plurality of compartments, an elevator disposed adjacent the rack for receiving balls from the table at its lower end portion and discharging said balls at its upper end portion, an adjustable member for positioning selectively adjacent the compartments for receiving the balls from the elevator and directing said balls into the selected compartments, and means for releasably retaining the shiftable member in adjusted position, said means comprising a notched bar, and a spring pressed keeper slidably mounted on the shiftable member for engagement in the notches in the bar. 70

2. A ball racking device for pool tables having a ball receiving tray communicating with the table pockets comprising a rack having a plurality of superposed, inclined ball receiving compartments, said compartments open at their upper ends, a closure for the lower ends of the compartments, an elevator disposed adjacent the open ends of the compartments and spaced therefrom, a conduit connecting a lower portion of the elevator with the tray for the passage of balls from said tray to the elevator, said elevator adapted to discharge the balls at its upper end portion, means for actuating the elevator, a rack bar mounted for vertical movement adjacent the open ends of the compartments, means for actuating the rack bar, a bridge member fixed on the upper end of the rack bar and disposed between the rack and the elevator and adapted to be selectively positioned adjacent the open ends of the compartments in a manner to receive the balls from the elevator and direct said balls into the selected compartment. 85

3. A ball racking device for pool tables having a ball receiving tray communicating with the table pockets comprising a rack having a plurality of superposed, inclined ball receiving compartments, said compartments open at their upper ends, a closure for the lower ends of the compartments, an elevator disposed adjacent the open ends of the compartments and spaced therefrom, a conduit connecting a lower portion of the elevator with the tray for the passage of balls from said tray to the elevator, said elevator adapted to discharge the balls at its upper end portion, means for actuating the elevator, a rack bar mounted for vertical movement adjacent the open ends of the compartments, means for actuating the rack bar, a bridge member fixed on the upper end of the rack bar and disposed between the rack and the elevator and adapted to be selectively positioned adjacent the open ends of the compartments in a manner to receive the balls from the elevator and direct said balls into the selected compartment. 90

4. A ball racking device for pool tables having a ball receiving tray communicating with the table pockets comprising a rack having a plurality of superposed, inclined ball receiving compartments, said compartments open at their upper ends, a closure for the lower ends of the compartments, an elevator disposed adjacent the open ends of the compartments and spaced therefrom, a conduit connecting a lower portion of the elevator with the tray for the passage of balls from said tray to the elevator, said elevator adapted to discharge the balls at its upper end portion, means for actuating the elevator, a rack bar mounted for vertical movement adjacent the open ends of the compartments, means for actuating the rack bar, a bridge member fixed on the upper end of the rack bar and disposed between the rack and the elevator and adapted to be selectively positioned adjacent the open ends of the compartments in a manner to receive the balls from the elevator and direct said balls into the selected compartment, a vertically disposed bar mounted on the elevator and having a series of notches therein, a spring pressed keeper slidably mounted on the bridge member and engageable in the notches in the bar for releasably retaining the bridge member in adjusted position. 95

5. A ball racking device for pool tables having a ball receiving tray communicating with the table pockets comprising a rack having a plurality of superposed, inclined ball receiving compartments, said compartments open at their upper ends, a closure for the lower ends of the compartments, an elevator disposed adjacent the open ends of the compartments and spaced therefrom, a conduit connecting a lower portion of the elevator with the tray for the passage of balls from said tray to the elevator, said elevator adapted to discharge the balls at its upper end portion, means for actuating the elevator, a rack bar mounted for vertical movement adjacent the open ends of the compartments, means for actuating the rack bar, a bridge member fixed on the upper end of the rack bar and disposed between the rack and the elevator and adapted to be selectively positioned adjacent the open ends of the compartments in a manner to receive the balls from the elevator and direct said balls into the selected compartment, a vertically disposed bar mounted on the elevator and having a series of notches therein, a spring pressed keeper slidably mounted on the bridge member and engageable in the notches in the bar for releasably retaining the bridge member in adjusted position, and an elongated plate mounted on the bridge member and extend- 100

105

110

115

120

125

ing upwardly therefrom and movable therewith, said plate having an opening in its lower end portion for the passage of the balls into the selected compartment, said 5 plate constituting a closure for the open ends of the compartments which are above the selected compartment for preventing the entrance of the balls thereto.

6. A ball racking device for pool tables having a ball receiving tray communicating with the table pockets comprising, in combination, a rack including a plurality of inclined, superposed ball receiving compartments, said compartments open at their upper ends, means at the lower ends of the compartments for releasably retaining the balls therein, a tubular casing disposed vertically adjacent the open ends of the compartments and spaced therefrom, said casing having a vertically extending channel in its inner periphery, a spiral conveyor operatively mounted in the casing, means for actuating the spiral conveyor, an inclined conduit having one end connected to the tray for receiving balls

25 and connected to the tray for receiving balls therefrom and its other end connected to the channel for discharging the balls into the lower end thereof, said balls protruding from the channel into the casing and engageable by the spiral conveyor to be elevated thereby, a
30 laterally extending discharge neck at the upper end of the channel for discharging the balls therefrom, a guide disposed adjacent the casing, a rack bar mounted for vertical reciprocation in the guide, a bridge member
35 fixed on the upper end of the rack bar for vertical movement therewith for selective disposition adjacent the open ends of the rack compartments for receiving balls from the discharge neck and directing said balls into
40 the selected compartments, said bridge member having a ball receiving channel in its upper side inclined toward the compartments, means for raising and lowering the rack bar.

7. A ball racking device for pool tables
45 having a ball receiving tray communicating
with the table pockets comprising, in combi-
nation, a rack including a plurality of in-
clined, superposed ball receiving compар-
ments, said compartments open at their up-
50 per ends, means at the lower ends of the com-
partments for releasably retaining the balls
therein, a tubular casing disposed vertically
adjacent the open ends of the compartments
and spaced therefrom, said casing having a
55 vertically extending channel in its inner pe-
riphery, a spiral conveyor operatively mount-
ed in the casing, means for actuating the
spiral conveyor, an inclined conduit having
one end connected to the tray for receiving
60 balls therefrom and its other end connected
to the channel for discharging the balls into
the lower end thereof, said balls protruding
from the channel into the casing and en-
gageable by the spiral conveyor to be ele-
65 vated thereby, a laterally extending discharge

neck at the upper end of the channel for discharging the balls therefrom, a guide disposed adjacent the casing, a rack bar mounted for vertical reciprocation in the guide, a bridge member fixed on the upper end of the rack bar for vertical movement therewith for selective disposition adjacent the open ends of the rack compartments for receiving balls from the discharge neck and directing said balls into the selected compartments, said bridge member having a ball receiving channel in its upper side inclined toward the compartments, means for raising and lowering the rack bar, an elongated plate rigidly mounted on the bridge member and extending upwardly therefrom, said plate having an opening in its lower end portion for the passage of the balls into the selected compartments, said plate constituting a closure for the open ends of the compartments which are disposed above the selected compartment for preventing the entrance of the balls thereto, and means for releasably retaining the bridge member in adjusted position.

8. A ball racking device for pool tables having a ball receiving tray communicating with the table pockets comprising, in combination, a rack including a plurality of inclined, superposed ball receiving compartments, said compartments open at their upper ends, means at the lower ends of the compartments for releasably retaining the balls therein, a tubular casing disposed vertically adjacent the open ends of the compartments and spaced therefrom, said casing having a ver-

10
tically extending channel in its inner periphery, a spiral conveyor operatively mounted in the casing, means for actuating the spiral conveyor, an inclined conduit having one end connected to the tray for receiving balls therefrom and its other end connected to the channel for discharging the balls into the lower end thereof, said balls protruding from

the channel into the casing and engageable by the spiral conveyor to be elevated thereby, a laterally extending discharge neck at the upper end of the channel for discharging the balls therefrom, a guide disposed adjacent the casing, a rack bar mounted for vertical reciprocation in the guide, a bridge member fixed on the upper end of the rack bar for vertical movement therewith for selective disposition adjacent the open ends of the rack compartments for receiving balls from the discharge neck and directing said balls into the selected compartments, said bridge member having a ball receiving channel in its upper side inclined toward the compartments, means for raising and lowering the rack bar, an elongated plate rigidly mounted on the bridge member and extending upwardly therefrom, said plate having an opening in its lower end portion for the passage of the balls into the selected compartments, said plate constituting a closure for

the open ends of the compartments which are disposed above the selected compartment for preventing the entrance of the balls thereinto, and means for releasably retaining the bridge member in adjusted position, the last named means comprising a vertically disposed bar having a series of substantially V-

shaped notches therein, a keeper slidably mounted on the bridge member and engageable in the notches, and resilient means operatively engaged with the keeper for yieldingly urging the same into the notches. 70
